UNITED STATES PATENT OFFICE.

FREDERICK J. OSIUS, OF RACINE, WISCONSIN.

SHOW-CASE WINDOW.

SPECIFICATION forming part of Letters Patent No. 774,268, dated November 8, 1904.

Application filed February 13, 1904. Serial No. 193,370. (No model.)

To all whom it may concern:

Be it known that I, FREDERICK J. OSIUS, a citizen of the United States, and a resident of Racine, in the county of Racine and State of Wisconsin, have invented certain new and useful Improvements in Show-Case, Windows; and I do hereby declare that the following is a full, clear, and exact description thereof.

My invention has for its object to provide show-case windows adjustable to project a predetermined distance from building-walls and which in retracted position are flush with said walls, said invention consisting in what is hereinafter particularly set forth with reference to the accompanying drawings and subsequently claimed.

Figure 1 of the drawings represents a vertical longitudinal section view of an adjustable show-case window in accordance with my invention; and Fig. 2, a horizontal section of the same, having parts thereof broken away.

Referring by letter to the drawings, A indicates a building-wall provided with an opening for a partly-glazed show-case B, constituting a window that may be projected a predetermined distance from said wall and retracted flush with the same. Back of the show-case is a platform C, the frame of this platform and that of said show-case being a unitary structure the parts of which are preferably flat and angle-pieces of steel suitably united. As herein shown, the floor of the show-case is a continuation of the top of the platform; but in some instances said floor may be omitted to disclose drawers and their contents forward of said platform.

Rails D are provided in the frame, and stationary standards E, on the floor of the apartment back of the wall A, are provided with lateral studs on which wheels F are arranged over and under the rails with which they are in contact, these wheels being shown in full and dotted lines.

Mounted to turn in the frame, transversely thereof under the top of the platform, are parallel shafts G H, and link belts I engage sprocket-wheels J, that are fast on the shafts, said belts being connected by pins b or other suitable means with arms c of a pair of the aforesaid standards. Another shaft, K, in a

hanger d, attached to a rear upper transverse bar of the frame, has bevel-gear connection with the shaft G and is operated by a crank-wheel L to effect adjustment of said frame.

A rock-shaft M has its bearings in the frame transversely of the same, and a cross-head e of this rock-shaft is connected to vertical bolt-rods N P, guided in said frame. The ceiling and floor of the apartment aforesaid are provided with bolt-rod keepers f g, adjacent to the wall A, and a crank h of the rock-shaft is connected by a link-rod i with a lever Q in fulcrum connection with the aforesaid frame, at the rear thereof.

The front of the show-case being flush with the wall A, the crank-wheel L is operated to project said show-case a predetermined distance from said wall and the lever Q actuated to shoot the bolt-rods N P into their keepers, thus locking said show-case in adjusted position. These operations are reversed when it is desirable to retract the show-case.

From the foregoing it will be understood that a window show-case in accordance with my invention may be projected to encroach on a sidewalk the legal limit allowed for portable show-cases, this being a particular advantage of said invention, and said window show-case may be constructed with especial reference to the sale of goods therefrom on the sidewalk, the details of the aforesaid invention being susceptible of indefinite variation as circumstances may require.

Having thus described my invention, what I claim as new, and desire to secure by Letters Patent, is—

1. A show-case constituting a window having the lower portion of its frame rearwardly extended and means in conjunction with the frame for projecting and retracting the show-case with respect to an adjacent building-wall.

2. A show-case constituting a window having the lower portion of its frame rearwardly extended, means in conjunction with the frame for projecting and retracting the show-case with respect to an adjacent building-wall, and means for locking said show-case in adjusted position.

3. A show-case constituting a window having the lower portion of its frame rearwardly

extended, rails provided in said lower portion of the frame, rail-opposing wheels having stationary bearings within an apartment lighted by the window, and means for traveling the 5 rails in contact with the wheels.

4. A show-case constituting a window having the lower portion of its frame rearwardly extended, rails provided in the frame, standards in an apartment lighted by the window, 10 wheels on studs of the standards in pairs above and below the rails with which they are in contact, shafts mounted in said frame, sprocket-wheels on the shafts, link belts on the sprocket-wheels and each connected to a standard, and 15 a power-shaft hung in the aforesaid frame in gear connection with one of the shafts aforesaid.

5. A show-case constituting a window having the lower portion of its frame rearwardly 20 extended, means in conjunction with the frame for projecting and retracting the show-case, bolt-rods guided in the frame, a rock-shaft

mounted in the frame and provided with a cross-head connected to the bolt-rods, a lever in fulcrum connection with the frame, and a 25 link-rod connecting the lever with a crank of the rock-shaft, suitably-arranged keepers being provided for said bolt-rods.

6. A show-case constituting a window, a platform rearward from the show-case, the 30 frame for said show-case and that of the platform being unitary, and means in conjunction with the frame for projecting and retracting the show-case with respect to an adjacent building-wall.

In testimony that I claim the foregoing I have hereunto set my hand, at Racine, in the county of Racine and State of Wisconsin, in the presence of two witnesses.

FREDERICK J. OSIUS.
